UNITED STATES PATENT OFFICE

ARNOLD GLADSTONE SLADDIN, OF BRIGHOUSE, ENGLAND

PAD FOR GARMENTS

Application filed May 17, 1927, Serial No. 191,991, and in Great Britain November 20, 1926.

This invention relates to an improvement in or modification of the invention described and claimed in my Patent Number 1,698,144, granted January 8, 1929, and has for its object an improved pad and a cheaper production thereof.

In constructing garment pads in the manner described in the above-mentioned patent, certain or all of the shaped layers of cotton wadding or wadding comprising other suitable loose fibres provided normally with a film of dried size upon one side thereof, are given a film or thin coat of wet or liquid size upon their unglazed sides, the several superimposed layers being relatively arranged in a particular manner whereby on being pressed together the wet size more or less penetrates the contacting surfaces causing the whole of the layers to cohere.

The additional film of liquid size and its application adds to the cost of production and tends to set up a stiffness or hardness in the pad which it is desired to avoid, therefore, in the present invention the use of liquid size is dispensed with, the covering folds or layers are arranged with the glazed or sized surfaces upon the outside and the intermediate folds or layers arranged with the glazed surface of one fold adapted to make contact with the unglazed surface of another fold, the superimposed folds differing in size but of the same shape, so arranged, are placed within a mould, receptacle or the like wherein they are subjected to moist heat which causes the normally glazed surfaces to become sticky or tacky and to adhere to the unglazed surfaces thus causing the whole of the folds to cohere. When this has been accomplished the moist heat is substituted by a dry heat or by a vacuum, which operates to produce a garment pad substantially homogeneous adapted to retain its shape under all conditions, and of maximum softness and resilience.

I attain these objects by the means illustrated in the accompanying drawing, in which:—

Fig. 1 is a front view of one example of a pad for garments constructed according to this invention, showing in broken lines the

relatively different sized folds or layers of normally sized cotton wadding, forming the intermediate folds.

Fig. 2 is a side elevation of the folds or layers employed in the construction of the pad shown at Fig. 1, showing the arrangement of the folds relatively to the glazed and unglazed surfaces thereof.

Fig. 3 is a similar view to Fig. 2 showing the stage of manufacture of the pad ready for being placed in the mould for fixing the folds together.

Fig. 4 is a modification of Fig. 2 showing the intermediate folds composed of unglazed wadding.

Fig. 5 is a sectional side elevation through the line 2—2 of Fig. 1, showing the shape of the pad upon being taken out of the mould.

Referring to the drawing:—The several folds or layers A of cotton wadding cut to a predetermined shape and of different sizes are relatively arranged and superimposed with the glazed surface B of one layer next the unglazed surface C of another layer, one of the covering layers D being preferably glazed upon both sides. It will be observed that by this method and at this stage of the operation the glazed layers, which are cut from a sheet of normal previously sized wadding, are in a dry state with the layers being more or less detached from each other although in their correct positions.

The dry glazed surfaces B of the layers having originally been formed of an adhesive such as size, these surfaces may be again rendered sticky or adhesive by the application or placing of a moisture saturated cloth over the superimposed layers and the whole subsequently subjected to pressure by a hot iron particularly on the outer edges, which softens the glazed surfaces and causes the whole of the layers to cohere. The same result may be more effectually obtained by submitting the said superimposed layers to the action of a suitable steam pressing machine, the drying process being effected therein by vacuum.

The garment pad thus produced possesses the maximum softness and pliability in addition to other advantages mentioned with reference to my former patent.

The arrangement of the layers of glazed cotton wadding may be varied as desired, for instance, the two covering layers of the pad may both be cut or formed from wadding having only one glazed surface, and their glazed surfaces placed to the inside of the pad, thereby presenting an extra soft though stable outer surface to both sides of the cover, which may be ironed or otherwise, as desired. Further, the whole or part of the inner layers may consist of loose carded unglazed wadding (as shown at Fig. 4), if desired.

What I claim as my invention, and desire to secure by Letters Patent, is:—

15 The process of forming laminated pads for garments comprising cutting from a sheet of fibre wadding having preliminarily applied thereto a film of dry fusible sizing attached to one side, two layers of the same dimension, 20 two additional layers each of different dimensions and each smaller than the first mentioned layers, one of the first mentioned layers having preliminarily applied thereto an adhesive film of dry fusible sizing upon the opposite side thereof, disposing the two smaller layers between the two first mentioned layers with the sizing of each layer exposed to the unsized surface of the adjacent layer, arranging the layers while loosely disposed in 25 proper final position to form the pad, and subjecting the said layers to pressure and moisture to fuse the films of sizing and bind the plurality of layers together to form a composite pad.

30 35 In testimony whereof I affix my signature.
ARNOLD GLADSTONE SLADDIN.
